ABSTRACT

An electric circuit is disclosed for starting an output member in vibratory motion and maintaining the vibrations at a constant amplitude. A coil is electromagnetically coupled to the output member and performs both the driving and pick-up functions. The circuit includes two oppositely polarized transistors cooperating with a coupling capacitor to deliver current pulses of a relatively large pulse width to the coil to start the output member in vibratory motion. The pulse width is progressively decreased until the output member is vibrationally maintained at a constant amplitude and frequency.

FIG. 6

CIRCUIT FOR DRIVING A MOVING ELEMENT

This invention relates to a driving circuit for driving a moving element and more specifically relates to a mechanical vibrator or motor rotor for use as a reference vibrator or oscillator for timepieces.

A variety of driving circuits are known for driving mechanical vibrators, for example, tuning forks and balance wheels, as reference vibrators for timepieces. One such known circuit comprises an astable multioscillator, a coil coupled as a load to the astable multioscillator which combines pick-up and driving functions, and a vibrator having attached thereto a magnet. In such a circuit, the coil coacts with the magnet to serve as a transducer and the astable multioscillator is triggered by an electric signal induced in the coil by the vibratory motion of the vibrator to drive the vibrator. In the conventional driving circuit above described, the pulse width of the driving pulse is kept constant and consequently the vibrator cannot be supplied with a sufficient pulse for its starting. Therefore, the vibrator is incapable of self-starting and must initially be driven by an external force. The same drawback applies to the type of ordinary driving circuit wherein a motor is used instead of a mechanical vibrator; here again, the motor cannot start by itself.

The present invention eliminates the foregoing disadvantages of the existing vibrator driving circuits and provides a new, improved driving circuit.

According to one aspect of the present invention, a driving circuit for a moving element is provided which comprises first and second transistors having opposite polarities connected such that the collector of the first transistor is serially coupled to the base of the second transistor and a biasing resistor is connected between the base of the first transistor and a power source. Another resistor is connected to the emitter of the first transistor and the emitters of both transistors are capacitively coupled to each other. A coil is electromagnetically coupled to a moving element and combines the function of driving the moving element with the function of picking up the motion of the moving element. The coil is connected to the emitter of the second transistor and a d-c voltage source is connected to constitute a series circuit with the resistors, capacitor and coil. Thus, the pulse of driving current that is supplied by the coil to the moving element has a sufficiently large pulse width at the time of starting to effect self-starting of the moving element.

Once the moving element has started its motion, the coil picks up the motion and the electric signal thereby induced is superposed on the base-to-emitter voltage to trigger the transistors. As the moving element approaches a steady motion, a driving current with a progressively decreasing pulse width is automatically developed and applied. This results in small power consumption during the steady motion. Also, a driving force synchronized with the motion of the moving element is obtained.

It is an object of the present invention to provide a driving circuit capable of self-starting the motion of the moving element and minimizing the power consumption during the steady motion of the moving element.

Another object of the present invention is to provide a driving circuit which is simplified in construction, inexpensive to manufacture, and adapted for mass production.

Other features, advantages, and objects of this invention will become apparent from the following detailed description taken in conjunction with the accompanying drawings, in which:

FIG. 1 is a diagram of a driving circuit according to the present invention;

FIG. 2 is a diagrammatic plan view, on an enlarged scale, of the transducer shown in FIG. 1;

FIG. 3A is a wave form explanatory of the condenser voltage;

FIG. 3B is a wave form explanatory of the base-to-emitter voltage of the transistor;

FIG. 3C is a wave form explanatory of the current that flows through the coil;

FIG. 4 is a diagram of another embodiment of driving circuit embodying the present invention;

FIG. 5 is a diagram of still another form of driving circuit embodying the present invention; and

FIG. 6 is a diagram of yet another form of driving circuit embodying the present invention.

Referring specifically to FIG. 1, there is shown a driving circuit employing a balance wheel 1 as the output or moving element. The balance wheel together with a coil L, which is electromagnetically coupled with the balance wheel 1, comprise a transducer which combines the pick-up and driving functions. The balance wheel 1, as better shown in FIG. 2, consists of a rotatably mounted center shaft 2, a disk 3 supported by the shaft, a permanent magnet 4 fixed to the upper surface of the disk 3, and a mass 5 functioning as a counterbalance. The ring-shaped coil L is secured in position so that when the disk 3 rotates, the magnet 4 passes thereunder. The coil L converts an electric signal applied thereto into a mechanical motion of the balance wheel 1 and, at the same time, picks up the mechanical motion of the balance wheel 1 and converts the same into an electric signal. In other words, it combines both functions of driving and pick-up coils. The collector of an NPN transistor Tr_1 and the base of a PNP transistor Tr_2 are serially coupled and a resistor R_2 is connected between the base of the transistor Tr_1 and the positive terminal of a power source E to bias the transistor Tr_1 in the forward direction. To the emitter of the transistor Tr_1 is connected a resistor R_1 . Between the emitters of the two transistors Tr_1 and Tr_2 , a condenser C is connected for capacitive coupling of the two emitters. The combined pick-up and driving coil L is connected to the emitter of the transistor Tr_2 . The positive terminal of the power source E, coil L, condenser C, resistor R_1 , a switch S, and the negative terminal of the power source E are connected together in a series circuit. The collector of the transistor Tr_2 is connected to the switch S. Thus, four component circuits are formed: i.e., a charge loop consisting of the power source E, coil L, condenser C, resistor R_1 , and switch S; a discharge loop consisting of the condenser C, emitter and base of the transistor Tr_2 and collector and emitter of the transistor Tr_1 ; a branched discharge loop consisting of the condenser C, emitter and collector of the transistor Tr_2 , and resistor R_1 ; and an oscillating circuit consisting of the power source E, coil L, emitter and collector of the transistor Tr_2 , and the switch S.

The operation of this driving circuit will now be explained with reference to the graphs of FIG. 3. When the switch S is closed, the base and emitter of the

transistor Tr_1 are biased in the forward direction, but the transistor Tr_1 remains in the OFF position because the condenser C is charged by the charge loop.

FIG. 3A gives time t on the axis of abscissa and the voltage V_C in the condenser C on the axis of ordinate. By the charge loop, the condenser voltage as represented by a wave form a_0 is increased up to a certain level A_1 . In FIG. 3B, time t is plotted on the axis of abscissa against the base-to-emitter voltage V_{BE} of the transistor Tr_1 on the axis of ordinate. While the condenser C is being charged, the voltage as represented by a wave form b_0 rises to the level B_1 . The transistor Tr_1 is switched ON when its base-to-emitter voltage reaches the level B_1 . Accordingly, the charge on the condenser C begins to be discharged by the discharge loop, through the circuit composed of the emitter and base of the transistor Tr_2 , collector and emitter of the transistor Tr_1 , and condenser C. At the same time, the transistor Tr_2 is instantaneously switched ON, whereupon a large current flows from the power source E through the coil L and the emitter and collector of transistor Tr_2 . On the other hand, the discharge current from the condenser C is also branched through the loop composed of the emitter and collector of the transistor Tr_2 , resistor R_1 and condenser C. Thereupon, the condenser voltage drops as represented by a wave form a_1 in FIG. 3A and the base-to-emitter voltage of the transistor Tr_1 is increased and maintained by the branched discharge to a level B_2 in FIG. 3B. The charge on the condenser C is discharged by a time constant which is governed by the capacity of the condenser C, the resistance value of the resistor R_1 and the resistance components of the transistors Tr_1 and Tr_2 . When the voltage of the condenser C drops to A_2 , the transistor Tr_1 is switched OFF and the transistor Tr_2 is immediately turned OFF, too. FIG. 3C, in which time t is plotted on the axis of abscissa against the current I_L that flows through the coil L on the axis of ordinate, shows a driving pulse current e_0 flowing through the coil L. As the transistor Tr_2 is switched OFF, the condenser C is charged again, and the cycle of operation above described is repeated to carry out astable oscillation.

The period of the astable oscillation is set at a frequency greater than the natural frequency of the moving element, and the driving pulse current e_0 is set at a value that can give a sufficient driving force to effect starting of the moving element.

The balance wheel 1 is started by the driving pulse current e_0 , and an induced voltage is produced in the coil L. Thus, the base-to-emitter voltage of the transistor Tr_1 is applied with a wave form b_1 , or the wave form b_0 shown in FIG. 3B superposed with the induced voltage. With the attainment of the voltage B_1 , the transistor Tr_1 is triggered. At this time the condenser C is charged as with the wave form a_2 to a voltage A_3 . The transistor Tr_1 is switched ON with the base-to-emitter voltage B_1 , while, in the manner already described, the transistor Tr_2 is switched ON by the discharge current which is dictated by the time constant of the condenser C, with the result that the condenser C discharges as represented by the wave form a_3 and the driving pulse current e_1 flows through the coil L, thereby driving the balance wheel 1. As the procedure above described is repeated and the amplitude of the balance wheel 1 is gradually increased,

the induced voltage also rises and is applied as such to the base-to-emitter voltage, thus increasing the frequency at which the transistor Tr_1 is triggered. Accordingly, the charging and discharging intervals of the condenser C are shortened by degrees. The pulse width of the driving pulse current that flows through the coil L while the transistor Tr_2 is ON is steadily decreased. When the balance wheel 1 has attained a state of steady vibration with a constant amplitude and frequency, the pulse current also becomes a stable and steady driving pulse current e having a predetermined pulse width. Hence, the balance wheel 1 sustains its steady vibration.

Since the driving pulse current e_0 that acts on the vibrator while the vibrator is kept still in the manner above described is much larger than the driving pulse current e that acts when the vibrator has attained the state of steady vibration, the vibrator can start by itself without the necessity of an external force being applied thereto. When the vibrator attains its steady vibration, the vibrator is driven by a driving pulse current e having a much narrower pulse width than the starting pulse widths and, accordingly, the power loss is reduced to a minimum. Another feature is that the vibrator is driven with a pulse current that is produced at a frequency synchronized with the natural frequency of the vibrator.

By relocating the two transistors and coupling the power source with the terminals reversed, it is possible to obtain another embodiment of the invention. The operation of the resulting driving circuit is entirely the same as that of the circuit illustrated in FIG. 1.

Another embodiment of the present invention will now be explained with reference to FIG. 4. In this embodiment, a driving circuit having a transducer equipped with a tuning bar 16 instead of the balance wheel 1 is used. The tuning bar 16 of the transducer is fixed at one end and is provided at its free end with a magnet bar 17 attached to one side and with a mass 18 attached to the other side effective to counterbalance the weight of the magnet bar. A ring-shaped coil L_{10} is secured in place such that the magnet bar 17 is slidable with respect thereto. In the driving circuit shown, a thermistor $R_{th,10}$ is connected between the collector of the transistor Tr_{11} and the emitter of the transistor Tr_{12} . In the figure, reference symbols E_{10} , S_{10} , R_{11} , C_{10} and R_{12} denote parts similar to their counterparts in FIG. 1. In this embodiment, the temperature characteristics of the transistors Tr_{11} and Tr_{12} can be improved.

FIG. 5 shows another embodiment of a driving circuit having a transducer in which the moving element is a rotor 29 of a motor. The rotor 29 is a ferrite disk mounted on a journalled shaft 30 and has two pairs of magnetic poles N and S. A ring-shaped coil L_{20} combining the pick-up and driving functions is fixed in spaced relation to the poles on the rotor 29. Further, in the driving circuit shown, a condenser C_{21} is connected between the base and collector of the transistor Tr_{21} . In the diagram, symbols C_{21} , Tr_{21} , L_{20} , E_{20} , S_{20} , C_{20} , Tr_{22} , R_{21} and R_{22} represent parts similar to their counterparts in FIG. 1. In this embodiment, the oscillation of the transistor Tr_{21} can effectively be prevented.

FIG. 6 shows still another embodiment of a driving circuit in which a condenser C_{31} is connected in parallel with a resistor R_{32} between the base of a transistor Tr_{31}

and the positive terminal of a power source E_{30} . In the diagram, symbols Tr_{31} , C_{31} , L_{30} , S_{30} , C_{30} , Tr_{32} and R_{31} indicate parts which are substantially equivalent to their counterparts in FIG. 1. In this embodiment, the driving pulse current can be advantageously shaped as desired.

What I claim and desire to Secure By Letters Patent is:

1. A circuit for driving a moving element comprising: a movably mounted output element, two transistors of opposite polarities, means serially connecting the collector of one of said transistors to the base of the other transistor, a d-c power source, a biasing resistor connected between the base of said one transistor and said

power source, another resistor connected between the emitter of said one transistor and said power source, means capacitively coupling together the emitters of said transistors, a coil electromagnetically coupled to said output element and electrically connected to the emitter of said other transistor effective to both vibrationally drive said output element and pick-up the movement of the vibrating output element, means connecting the collector of said other transistor to said power source, and means electrically connecting said power source, said other resistor, said capacitor and coil in series.
